UNITED STATES PATENT OFFICE.

ROBERT S. RILEY, OF WORCESTER, MASSACHUSETTS, ASSIGNOR TO SANFORD RILEY STOKER CO., OF WORCESTER, MASSACHUSETTS, A CORPORATION OF MASSACHUSETTS.

FUEL-FEED CHUTE FOR UNDERFEED STOKERS.

Application filed December 31, 1921. Serial No. 526,289.

This invention relates to an underfeed stoker and particularly to the provision of means by which certain parts of the fuel feed chute may be readily removed and replaced 5 when worn.

It is customary to provide an inwardly enlarged fuel chute between the rear of the fuel hopper and the front end of the stoker retort. This chute extends through the front 10 wall of the stoker, and as heretofore made has partially supported the wall itself. Under these conditions the removal of the chute for repair or replacement has frequently resulted in weakening or destroying the wall.

15 It is the object of my present invention to provide a construction of feed chute in which provision is made for convenient removal and replacement of the parts most affected by wear and corrosion, and in which other 20 parts remain permanently in place, and firmly support the wall resting thereon.

25 My invention further relates to arrangements and combinations of parts which will be hereinafter described and more particularly pointed out in the appended claims.

A preferred form of my invention is shown in the drawings, in which—

Fig. 1 is a sectional elevation of my improved feed chute, taken along the line 1—1 30 in Fig. 2;

Fig. 2 is a rear elevation thereof, and

Fig. 3 is a detailed view of one of the inner side plates.

Referring to the drawings, I have shown 35 a portion 10 of the cylinder which supports the usual fuel hopper of an underfeed stoker and connects the same with the feed chute through which the fuel is admitted to the upper end of a retort. The cylinder 10 has 40 a rearwardly extended portion 10^a which projects a considerable distance into the front wall 11 of the furnace, and may be supported upon a post 12, embedded in the lower portion of the wall.

45 This rearwardly extended position 10^a of the cylinder member 10 is substantially U-shape in cross-section, as clearly shown in Fig. 2, and may be provided with guide- 50 openings 13 to receive slide rods which operate the movable side walls of a certain type of stoker.

A bell-shaped top-plate 14 is supported above the rearwardly extended portion 10^a of the cylinder 10 in any convenient manner

as by plates 14^a which are embedded in the brick work of the furnace wall.

Upwardly extending flanges 15 prevent lateral displacement of the top plate 14, and relatively small depending lugs or projections 16 (Fig. 1) are provided for a purpose 60 to be described. At its front end, the plate 14 is secured by bolts 17 to a flange 18 formed on the cylinder 10.

A bell-shaped bottom plate 20 is disposed within the inwardly extending portion 10^a 65 of the cylinder 10 and is secured to the cylinder 10 at its front end by a bolt 21. The nut for the bolt is located in an opening 22 in a downwardly extending post or lug 24 which also supports the plate 20 upon the inner lower surface of the portion 10^a of the cylinder 10. A lug 25 extends downwardly and rearwardly at the back end of the plate 20 and supports the front end of a plate 26 which forms a portion of the stoker retort, 70 the parts being secured together by a bolt or rivet 27 dropped into aligned openings therein.

A pair of side-plates 30 are mounted between the upright sides of the portion 10^a of the cylinder 10 (as shown in Fig. 2), their ends being secured to the flange of the cylinder by bolts 31. The nuts for these bolts are disposed in rectangular openings 32 in the plates, the bolts extending through suitable passages 33 therein. The plates 30 are wedge-shaped in outline and larger at their rear ends and are provided with notches 34 at their upper rear corners, adapted to receive the lugs 16 of the top plate 14. These lugs 90 16 thus act to prevent rearward displacement of the side plates in addition to the bolts 31. The wedge-shaped outline of the side plates also enables the plates to act as keys to hold the top and bottom plates firmly 95 in position.

Outward lateral movement of the side plates is likewise prevented by engagement thereof with the inwardly projected U-shaped end portion 10^a of the cylinder 10 100 which forms in effect outer side walls for the fuel chute.

Having described the construction of my new feed chute or casing, the advantages thereof will be clearly apparent, as the bottom plate 20 or the side plates 30 may be removed and replaced without disturbing the cylinder 10 extension 10^a or the top plate 14

which supports the wall 11. Furthermore, these removable plates 20 and 30 are all simple castings which may be quickly and easily made, and which may be replaced at small expense. In removing these parts, the bolt 27 is taken out and the bottom plate 26 is lifted from position. The bolts 31 are then loosened and the rear portions of the side plates 30 are pressed toward each other to clear the lugs 16. The plates may then be removed rearwardly after which the bolt 21 is loosened and the bottom plate 20 may be easily removed.

10 It has been found by experience that the parts of a stoker subject to contact with the fuel wear rapidly, partially due to abrasion by the fuel and partially to the fact that the sulphur and moisture in the fuel tends to evolve a weak acid which attacks the metal, particularly when it is freshly abraded by the fuel.

15 20 25 With my improved invention, these parts subject to rapid wear may be readily and easily replaced without replacing the more expensive portions of the stoker and the setting thereof.

30 Under conditions of severe service I contemplate the provision of parts made of acid-proof iron alloy or other acid-proof metal which will resist corrosion and reduce the frequency of replacement. One iron alloy satisfying these requirements includes in its composition 1.2% carbon, 13% silicon and fractional percentages of manganese, potassium and sulphur.

35 40 Having thus described my invention, it will be evident that changes and modifications can be made therein by those skilled in the art, within the scope and spirit of my invention as set forth in the claims, and I do not wish to be otherwise limited to the details herein disclosed, but what I claim is:—

45 1. In an underfeed stoker having a front wall, a fuel feed chute having a permanently positioned outer wall-supporting casting and a plurality of sectional renewable inner wearing members extending substantially through said outer casing from the

outside to the inside of said wall and forming the fuel-engaging portions of said chute, 50 said inner members being easily removable and replaceable in said casing.

2. A fuel feed chute for an underfeed stoker, comprising an outer member, a top plate supported thereby, and renewable inner members detachably secured within said outer member. 55

3. A feed chute for an underfeed stoker, comprising a U-shaped outer casing, a top plate supported thereby, and removable inner side and bottom plates detachably secured in said casing. 60

4. A feed chute for an underfeed stoker, comprising an outer load-supporting structure and an inner renewable wear-receiving structure including separate side and bottom plates detachably secured within said outer structure and easily removable therefrom. 65

5. A fuel feed chute for an underfeed 70 stoker comprising permanently positioned outer side walls, a top plate supported thereby, and inner side plates detachably secured in position between said outer side walls.

6. A feed chute for an underfeed stoker, 75 comprising an outer load-supporting structure including a top plate, a renewable bottom plate, and wedge-shaped inner side plates secured between the top and bottom plates, and preventing displacement thereof. 80

7. A fuel feed chute for an underfeed stoker, comprising an outer member, a top plate supported thereby, and renewable inner members detachably secured within said outer member, certain of said members being wedge-shaped and having shoulders engaged by said top plate to prevent rearward movement thereof. 85

8. A feed chute for an underfeed stoker, comprising an outer load-supporting structure and an inner wear-receiving structure formed of acid-proof metal. 90

In testimony whereof I have hereunto affixed my signature.

ROBERT SANFORD RILEY.
